CARTON

Robert B. Deem, Philadelphia, Pa., and George V. Thompson, Chicago, Ill., assignors to Container Corporation of America, Chicago, Ill., a corporation of Delaware

Application January 22, 1940, Serial No. 314,966

2 Claims. (Cl. 229—31)

The present invention relates to folding cartons and more particularly to that type of folding carton which is adapted to be readily set up from a flattened or knock-down condition.

Objects of the invention are to provide a generally improved and simplified carton of this type and to provide an improved form of means for locking the carton in its set-up condition, whereby likelihood of accidental disengagement of the locking parts will be substantially avoided.

Other and more detailed objects will appear as the description proceeds.

In the drawing:

Fig. 1 is a perspective view of a folding carton made in accordance with the present invention, such carton being shown in its set-up condition;

Fig. 2 is a fragmentary cross-sectional view taken substantially along line 2—2 of Fig. 1, illustrating the end construction of the carton;

Fig. 3 is a view of the carton showing same as it appears in a collapsed condition ready for shipment from the carton plant to the user; and

Fig. 4 is a plan view of the blank of the carton.

The carton of the present invention is of the so-called "automatic set-up" type of folding carton in which diagonally folded corner elements are employed and in which a locking strip or other form of locking means is provided on the inside face of the bottom wall for cooperation with an end wall locking flap, the edge portion of which is adapted to come into engagement with the locking means on the bottom wall.

The carton of the present invention finds particularly advantageous use in connection with cartons upon which it is desired to apply a wax coating treatment, the locking parts being so designed as to be effective even where the wax or other coating is applied in a relatively heavy or thick manner tending to partially fill the angle between the bottom wall and the edges of the locking means located thereon.

Referring more particularly to the drawing, the carton of the present invention is designated as a whole at 5, and is preferably formed from a suitable blank of folding carton board, as illustrated in Fig. 4, such blank being suitably cut and scored to provide a bottom 6, side walls 7, 7 and end walls 8, 8. In the present instance, the ends of each of the side and end walls are connected by integral corner portions 9, 9. These corner portions are defined from the side walls by score lines 10, 10 and from the end walls by score lines 11, 11. A central score line 12, 12 is formed in the corner portions enabling them to be folded so that approximately one-half of the

corner portion will lie against the other half. Thus, when the side and end walls are raised to vertical position, the corner portions will tend to lie flat against the interior faces of one of the walls. In the present instance, the corner portions are arranged to lie against the inner faces of the end walls.

In order to provide for an increased efficiency in the carton locking parts (to be presently described), the score lines 10, 10 are formed so as to converge outwardly of the side walls, thus causing the score lines to assume an angular relationship with the score lines 13, 13, of somewhat less than ninety degrees. The score lines

15 11, 11 are preferably formed in alignment with the score lines 13, 13. It is to be noted that the corner construction thus described will tend to cause the end walls of the carton to be inclined slightly inwardly when the carton has been set

20 up with the corner portions folded inwardly and lying against the inner faces of the end walls.

Strips 15, 15 are preferably provided secured to the bottom wall of the carton adjacent the score lines 14, 14 defining the end walls 8, 8 from

25 the bottom wall 6. The edge portions of these strips serve to provide locking abutments for engagement by locking flaps 16, 16 preferably formed as extensions on the end walls 8, 8 and being defined therefrom by score lines 17, 17.

30 The flap extensions 16, 16 are provided with deformable edge portions adapted to facilitate locking of the flaps against the locking strips 15, 15. In the present instance, the edges of the flap extensions 16, 16 are suitably notched to

35 form tab portions or elements 18, 18 constituting deformable portions on the edges of the flap extensions. The effective length of the extension flaps 16, including the tabs 18, is such as to cause the ends of the tabs to be somewhat deflected or deformed when the extension flaps 16, 16 come to their final position in juxtaposition with the infolded corner portions 9, 9.

In order to provide for effective locking of the flaps 16, the central portion of each flap is

45 preferably formed so as to be devoid of tab elements, such as tabs 18, 18. This is effected by forming notched or cutout portions 19, 19. It is apparent that the flaps 16 when so constructed cannot be locked at a central point but will normally be locked by engagement with at least one

50 of the inner lying tabs 18, 18. It has been found in practice that packing operators, in setting up a carton of this type, will be more accurate in securely engaging the end wall locking flap with the locking strip 15 when the locking ele-

ments are eliminated at the center of the flap extension.

Due to the inward inclination of the end edges of the side walls 7, 7, it is apparent that the end wall flap will be caused to swing about an axis or a hinge line which is approximately in the same vertical plane with the locking edges of the strips 15. Thus the flap extension 16 will normally come to rest in locking position when the edge portions thereof have reached substantially the lower point in their arc of travel.

For practical purposes the slight degree of movement of the end wall flap from the time it overrides the edge of the locking strip 15 until the point at which it comes to rest with the edges of tabs 18, 18 behind such strip, it may be considered as substantially a straight line movement due to the smallness of the arc involved. Thus, when the ends of tabs 18, 18 are somewhat deflected or deformed when they reach their final position in juxtaposition with their attached end walls, the ends of such tabs will be directed both inwardly and downwardly to engage the edges of the strips 15.

Side walls 7, 7 are, in the present instance, provided with flap extensions 21, 21 separated therefrom by score lines 22 permitting the flap extensions 21 to be folded down to overlie the top of the carton and form a partial closure therefor.

In using the carton herein described, the side walls with their attached flaps 21 and the corner connections 9, are preferably folded in superimposed relation over the bottom 6, as illustrated in Fig. 3. In this condition the carton may readily be set up by grasping the ends and forcing the end walls upwardly to cause a concurrent upward swinging of the side walls until both side and end walls reach a vertical position after which the end wall flaps 16 are folded inwardly and downwardly until they snap in behind the edges of the strips 15, 15. Due to the provision of the notched out opening 19, the operator setting up the carton will find it necessary in general to apply pressure at relatively spaced points on the end wall flap, thus causing at least the more centrally positioned of the tab elements 18, 18 to be engaged behind the strip.

In this manner the carton will be secured in its set-up condition with no likelihood of accidental collapse. Due to the inclination of the score lines 10, 10 defining the corner connections 9 from the side walls 7, the axis about which the flap 16 moves is disposed inwardly of the carton along a line which is approximately in alignment with the locking edge of the strip 15. By this arrangement the edge of the locking flap carrying the deformable tab elements 18, 18 will arrive at substantially the lowermost part of its movement when it has passed the locking edge of the strip 15. While the inward inclination of the score lines 10, 10 has the effect of producing a desirable relationship between the axis of movement of the flaps 16 with respect to the locking edge of the strip 15, this relationship does not unduly distort the carton for the reason that the parts of the end wall, when in set-up condition, are not engaged one upon the other in an extremely close manner. On the contrary, the natural tendency of the paperboard to resist bending produces a thickness or bulk in the overlapping parts which tends to compensate for the amount of inward deflection which the

inclined score lines 10, 10 will have the tendency to produce. Thus, in practice the exterior surface of the end walls will not have any pronounced inward inclination.

While both ends of the carton have been described as being identically formed, it is, of course, obvious that the invention may be applied solely to one end of a carton and the other end may be formed in any other desirable and convenient manner.

It is to be understood that reference to end and side walls herein is made for purposes of convenience of description and it is desired that the invention be considered as not limited to side and end walls of any particular dimension. Accordingly, the parts referred to as end walls could be greater in dimension than the parts referred to as the side walls.

While the present description sets forth a preferred embodiment of the invention, certain changes may be made in the construction without departing from the spirit of the invention, and it is therefore desired that the present embodiment be considered in all respects as illustrative and not restrictive, reference being had to the appended claims rather than to the foregoing description to indicate the scope of the invention.

We claim:

1. A folding carton formed from a paperboard blank comprising a bottom panel, side and end walls hinged respectively to the sides and ends of said bottom panel, diagonally foldable corner portions connecting the ends of each side wall with the adjacent ends of each end wall, score lines defining said corner portions from said side and end walls, those of said score lines defining the ends of said end walls being aligned with the sides of said bottom panel and those of said score lines defining each of said corner portions being disposed at an angle to each other somewhat greater than 90°, whereby said end walls will tend to assume a somewhat inwardly inclined position when said side and end walls are in upright position with said corner portions folded to lie against said end walls, a locking strip secured to said bottom wall in relatively close spaced relation to the inner face of each of said end walls, and an extension carried by each of said end walls having deformable tab elements on its outer edge portions and having an overall length somewhat greater than the height of its associated end wall, whereby said tab elements will become deformed by engagement with the top surfaces of said locking strips when said extensions are swung inwardly and downwardly, and whereby the edges of the deformed tab elements will lockingly engage the edges of said locking strips to prevent displacement of said extensions after the deformed tab elements clear the edges of said locking strips in the movement of said extensions into juxtaposition with their associated side walls.

2. A folding carton formed from a paperboard blank comprising a bottom panel, side and end walls hinged respectively to the sides and ends of said bottom panel, diagonally foldable corner portions connecting the ends of each side wall with the adjacent ends of each end wall, score lines defining said corner portions from said side and end walls, those of said score lines defining the ends of said end walls being aligned with the sides of said bottom panel and those of said score lines defining each of said corner portions being disposed at an angle to each other somewhat greater than 90° whereby said end walls will tend to assume a somewhat inwardly in-

clined position when said side and end walls are in upright position with said corner portions folded to lie against said end walls, a locking strip secured to said bottom wall in relatively close spaced relation to the inner face of each of said end walls, and an extension carried by each of said end walls having deformable tab elements on its outer edge portion adjacent the ends thereof on either side of centrally located cutaway sections, and having an overall length somewhat greater than the height of its associated end wall, whereby said tab elements will become deformed

10

by engagement with the top surfaces of said locking strips when said extensions are swung inwardly and downwardly, and whereby the edges of the deformed tab elements will lockingly engage the edges of said locking strips to prevent displacement of said extensions after the deformed tab elements clear the edges of said locking strips in the movement of said extensions into juxtaposition with their associated side walls.
